UNITED STATES PATENT OFFICE.

JOHN PHILEMON TRUESDELL, OF TIVERTON, RHODE ISLAND, ASSIGNOR OF ONE-HALF
TO JAMES K. LANNING, TRUSTEE, OF FALL RIVER, MASSACHUSETTS.

LAMP-BURNER.

1,271,103.

Specification of Letters Patent.

Patented July 2, 1918.

Application filed February 23, 1915. Serial No. 10,107.

To all whom it may concern:

Be it known that I, JOHN P. TRUESDELL, a citizen of the United States, and a resident of Tiverton, in the county of Newport and 5 State of Rhode Island, have invented an Improvement in Lamp-Burners, of which the following description, in connection with the accompanying drawings, is a specification, like characters on the drawings 10 representing like parts.

This invention relates to lamp burners.

In order that the principle of the invention may be readily understood, I shall describe one embodiment of my invention and 15 the best mode known to me for practising my method.

In the accompanying drawing,—

Figure 1 is a vertical, central section of 20 a lamp burner embodying my invention, and whereby my method may be practised; and

Fig. 2 is a transverse horizontal section upon the line 2—2 of Fig. 1.

In accordance with and in carrying out 25 my invention, I employ a liquid fuel which may for example be kerosene oil. The nature of the liquid fuel may be widely varied. I provide a suitable wick or other device to convey the liquid fuel through capillary action 30 from the source of supply. The said liquid fuel is prior to combustion converted into a vapor, and it is my belief that such vapor is converted into a gas which is fed to the flame and burned as a gas. I have 35 demonstrated that by my invention and without the use of a mantle or like device, I produce a white or substantially white flame burning with perfect combustion, and hence with no carbon or other deposit and without odor. The flame when extinguished 40 leaves no smoke, and experiments have shown that I obtain the same degree of light with one third less supply of oil, or conversely stated that I obtain two thirds more 45 candle power from the same supply of oil and also obtain a greater degree of heat, which I consider to be owing in part to what I believe to be the fact that the combustion occurs from a gas and not from a 50 vapor. Other important features of my invention will be set forth hereinafter.

Referring more particularly to the drawings, I have represented a lamp burner having a base 1 through which air to support combustion may be introduced through a

suitable number of openings 2, whereby the combustion-supporting air is supplied through the central draft passage 3. The form of the base 1 may be widely varied within the scope of my invention, and if desired it may be of such conical form as to result in the drawing of an additional supply of air through the enlarged base and the contracted conical portion thereof. The base 1 is provided with a suitable reservoir 4, the upper portion 5 whereof terminates in a ring-like part 6 whereon may be removably supported a cap-like member 7 having a beaded upper end 8 resting upon the top of the ring-like part 6. Formed 70 with or suitably secured to the reservoir portion 4 of the base is an inner wick tube 9 extending up through the reservoir to a suitable extent and herein represented as terminating at 10, said wick tube forming 75 a continuation of the central draft passage 3. Preferably secured to or formed with the cap portion 7 is the outer wick tube 11 terminating at the point 12, and positioned between said tubes is a wick 13 of any suitable construction. Any suitable means may be provided to elevate the wick with respect to the tubes 9, 11. For that purpose I have shown a ring 14 having a laterally projecting arm 15 and an upright arm 16 provided 80 with a rack 17 with which meshes the usual pinion adapted to be rotated by the disk 18. Any other suitable means for adjusting the wick may, however, be employed and the wick may be supported in any suitable 85 manner.

Resting in the base of the cup 7 and preferably secured thereto is a perforated member 19, herein represented as of inverted frusto-conical shape. The upper end thereof is beaded as represented at 20, and thereon is supported the so-called gallery 21 having an inwardly extending portion 22 to receive the lower end of the chimney 23 and an upwardly extending, somewhat dome-shaped portion 24 perforated as indicated at 25. Secured to the gallery 21 as by rivets 26 are spring arms 27 embracing the outer face of the chimney and extending downwardly and inwardly a suitable distance where they are secured in any suitable manner, as by rivets 28 to a sleeve 29 removably supported upon the outer wick tube 11. The construction is such that the said gallery together with the spring arms 27 and 100 105 110

the sleeve 29 may be removed from the lamp.

Formed with or suitably connected with the perforated portion 24 of the gallery and 5 upwardly extending therefrom is a ring-like portion or member 30 constituting a portion of the means for controlling the draft or air supply to the flame and, also constituting the outer wall of what I may 10 designate as the gas chamber 31 and into which the wick 13 may extend to a greater or less extent depending upon the size and character of the flame desired.

Radially inside the wick 13 I position a 15 tubular member 32 controlling and directing the air that is admitted through the central passage 3. Any suitable means may be provided vertically to adjust the said tube 32. Herein for the purpose I have represented a rod 33 connected to said tube at 20 34 and connected at its lower end 35 to an adjusting lever 36.

The said tube 32 is supported within and 25 preferably by the inner wick tube 9 and is preferably spaced therefrom throughout nearly its entire extent. For that purpose, I have represented the lower portion thereof as having struck therefrom radial wings or lugs 37, here shown as three in number and 30 which extend to and contact with the said inner wick tube 9. I have also represented the said tube as longitudinally slotted for a suitable distance at 38, so as to provide bars 39 which are outwardly bowed as indicated at 40, so as also to contact with the inner surface of the inner wick tube 9. Said tube may be longitudinally slotted at 35 spaced points as indicated at 41 and, above said bowed bars 40 the said tubular member 40 is represented as perforated at 42. I have here shown the said tubular member 32 as having a perforated cap portion 43 suitably secured thereto, but if desired the parts may be integrally formed. Preferably 45 said cap portion 43 is outwardly flared as indicated at 44; said flaring portion being preferably perforated. Said cap portion 43 has a closed top as shown at 45, which, however, may be provided with a suitable number 50 of air exit openings 46, whereby the shape of the flame may be controlled.

The air to support combustion is in this embodiment of my invention supplied at 55 four points, namely, exteriorly of the ring-like member 30, where it comes in contact with the lower portion of the chimney 23 and serves to cool the same; interiorly of the ring-like member 30, where it is admitted into the so-called gas-forming chamber 31; 60 between the cylindrical member 32 and the inner wick tube 9, whereby said wick tube 9 and the wick 13 are maintained cool or substantially so, the air entering at this point being also admitted to the so-called 65 gas forming chamber 31; and through the

cylindrical member 32, the air passing therefrom through the opening 43 to the flame. By reason of the fact that the wick holding tube 9 and the wick 13 are kept cool, all tendency of the flame to draw an excess quantity 70 of fuel from the reservoir 4 is prevented, and therefore the flame burns with perfect combustion and with a white or substantially white flame, without deposit and without smoke when the flame is extinguished. 75

The cylindrical member 32 may be very accurately adjusted vertically to any desired degree of fineness, and by such vertical adjustment the character of the flame is accurately controlled. By moving the said 80 cylindrical member 32 downward, the upper edge 47 thereof approaches more nearly to the upper edge of the ring-like member 30, and hence not only is the size of the so-called gas forming chamber 31 varied, but 85 the force of movement of and the amount of air applied to the flame through the said chamber 31 are controlled. The downward movement of the said cylindrical member 32 reduces the size of the flame, and moreover renders the same whiter and more brilliant, since the supply of air thereto is lessened. Careful experiments have demonstrated that the flame commences at the top 90 of the wick, and even when the wick is elevated more or less beyond the tops 10 and 12 of the tubes 9, 11, the flame does not creep back down the wick as has heretofore occurred in lamps with which I am familiar. Perfect combustion occurs with any size of 95 flame, that is at any candle power, and the flame burns without odor and without deposit. 100

The air supplied through the cylindrical member 32 is superheated at or before it 105 is discharged through the perforations 43. The air supplied to the flame at or through the chamber 31 is perfectly controlled, and in this embodiment of the invention through the regulation of the size of the chamber 110 31 and the division of the air supply as herein disclosed.

Having thus described one illustrative embodiment of my invention and the best mode known to be for carrying out my 115 method, I desire it to be understood that although specific terms are employed, they are used in a generic and descriptive sense and not for purposes of limitation, the scope of the invention being set forth in the 120 following claims.

Claims:

1. A liquid-fuel burner comprising in combination, means to contain a liquid fuel supply, a wick support, an air admission tube positioned interiorly of and having a portion spaced from said wick support, thereby to afford an air passage therebetween, said tube having a sliding engagement with said wick support, and a vertical 125 130

wall outside of the wick support and co-operating with said tube to form an upwardly uncontracted chamber above the wick.

5. 2. A liquid-fuel burner comprising in combination, means to contain a liquid fuel supply, a wick support, a tube 32 positioned interiorly of and having a portion spaced from said wick support, said tube extending to a point above the wick support and provided with an outwardly flaring upper end, and an upright wall radially outside of said wick support and co-operating with said inner tube to form a chamber.
10. 15. 3. A liquid-fuel burner comprising in combination, means to contain a liquid fuel supply, a wick support, a tube 32 spaced throughout a substantial portion of its length from but supported by said wick support, the upper portion of said tube being perforated and extending above said wick support, whereby air is admitted to the flame both between the wick support and said tube and through the tube, and an upright wall radially outside of said wick support and co-operating with said tube to form a chamber.
20. 25. 4. A liquid-fuel burner comprising in combination, means to contain a liquid fuel supply, a wick support, an air admission tube mounted within said wick support and having a closed, flat, upper end, and a short imperforate upright wall 30 radially outside of said wick support and terminating below the upper end of said tube, said tube and wall forming a chamber, and means for admitting air to said chamber both interiorly and exteriorly of the wick support.
30. 35. 5. A liquid-fuel burner comprising in combination, means to contain a liquid fuel supply, a wick support, an air admission tube mounted within said wick support and having a closed, flat, upper end, and a short, imperforate upright wall 30 radially outside of said wick support and terminating below the upper end of said tube, said tube and wall forming a chamber, and means for admitting air to said chamber both interiorly and exteriorly of the wick support, and means for admitting air radially outside of said outer wall.
40. 45. 50. 6. A liquid-fuel burner comprising in combination, means to contain a liquid fuel supply, a wick support, an air admission tube mounted within said chamber and hav-
- ing a closed, flat, upper end and a short, imperforate upright wall 30 radially outside of said wick support and terminating below the upper end of said tube, said tube and wall forming a chamber, means for admitting air to said chamber both interiorly and exteriorly of the wick support, and means for admitting air radially outside of said outer wall below the upper end of said inner tube.
65. 7. A liquid-fuel burner comprising, in combination, means to contain a liquid fuel supply, an annular wick tube extending therefrom, said wick tube constituting a central draft device supplying air internally to the base of the wick, a perforated gallery about said wick tube and a wall rising from said gallery and forming a chamber about the wick, an air conducting device extending into said wick tube and supplying air therefrom near the top of the flame in an outward direction substantially transverse to the axis of the tube.
70. 75. 8. A liquid-fuel burner comprising, in combination, means to contain a liquid fuel supply, a wick device to conduct liquid fuel therefrom, a chamber at the upper edge of said wick, means to admit air thereto and a member of varying cross section supported above said chamber, connections therefrom to the exterior of the burner and permitting manipulation while the burner is alight to adjust said member into and out from said chamber to vary the size thereof.
80. 85. 9. A liquid fuel burner comprising in combination a fuel reservoir, a wick support comprising concentric draft and wick tubes, a tube 33 extending for a substantial distance into said draft tube but spaced from the walls therefrom whereby to provide 90 for an air current at the periphery of the draft tube, said tube 33 extending beyond the draft tube and having provision for directing air outwardly to the flame beyond the wick, and means associated with the tube 95 permitting adjustment thereof while the burner is in use.
100. In testimony whereof, I have signed my name to this specification, in the presence of two subscribing witnesses.

JOHN PHILEMON TRUESDELL.
